UNITED STATES PATENT OFFICE

LEON COHEN, OF ST. LOUIS, MISSOURI.

HAT-PROTECTOR.

1,222,528.

Specification of Letters Patent. Patented Apr. 10, 1917.

Application filed September 2, 1915. Serial No. 48,717.

To all whom it may concern:

Be it known that I, LEON COHEN, a citizen of the United States, and resident of St. Louis, Missouri, have invented certain new and useful Improvements in Hat-Protectors, of which the following is a specification containing a full, clear, and exact description, reference being had to the accompanying drawings, forming a part hereof.

10 My invention relates to improvements in hat protectors, wherein two covers are employed, one to overlie the crown and brim of the hat and the other placed within the crown and underlying the brim.

15 The object of my invention is to produce an economical and slighty protection for hats, which snugly conforms thereto both inside and outside, to the end that soiling by dust or handling is obviated; and further to 20 provide a protector having the above characteristics and by which the material of the hat may be determined without removing the protector.

25 With the above object in view, my invention consists in certain novel details of the construction and arrangement of parts, hereinafter fully set forth, pointed out in my claims and illustrated by the accompanying drawings, in which—

30 Figure 1 shows in plan a hat provided with my improved protector, a portion of the outer protector being broken away; and

Fig. 2 is a side elevation, a portion of which is sectional and taken on the line 2—2 of Fig. 1.

Referring by numerals to the accompanying drawings:

5 designates a hat crown and 6 the brim thereof. The hat shown is constructed of straw braid and shaped by being pressed between blocking dies, but it is to be understood that the material designated and the shape shown may vary.

45 The numeral 7 designates the crown portion of a protector element which fits into the hat crown and which has an integral outstanding flange or brim 8 whose margin 9 is brought around to overlie the margin of the brim of the hat and is secured thereto by stitching as shown at 10.

55 The numeral 11 designates the crown portion of a protector element which fits over the hat crown and which has a flange or brim 12 arranged to overlie the upper surface of the hat brim and of substantially the same dimensions as the hat brim, and has

at its free margin a strip 13 secured to the protector brim by stitching.

By preference the protectors are constructed of impervious material such as 60 sheets of wax paper which are pressed between the dies from which the hat they are to fit is blocked. I find that wax paper is best adapted for my purpose in that it is not only impervious to dust, soiling by handling, 65 greases and the like, but is a material readily formed by the dies and which will best retain its shape after forming.

By shaping the protectors between the same dies which block or shape the hat, all 70 manual labor for such shaping is obviated, and the protectors fit snugly to the hat crown and brim to exclude dust.

The reinforcing strip when made of a piece of the braid or other material out of 75 which the hat is formed, identifies the material and color of the hat, without removing the protector, as well as stiffens the brim of the protector and causes it to hold its shape and remain in snug fitting placement on the 80 hat brim.

In addition to the uses heretofore described for my improved hat protector, it is obvious that it may be applied to any hat, and when so applied it not only protects 85 the hat in the manner heretofore described, but also it may be used for protection of a hat against moths, etc.

Having thus described my invention, what I claim as new therein and desire to secure 90 by Letters Patent of the United States therefor, is:

1. A protector for hats, comprising two sheets of impervious material, one of which is conformed to fit and cover the interior of 95 a hat crown and the lower surface of the brim, the other conformed to fit the exterior of the hat crown and upper surface of the brim, and means for holding the outer edges of the two sheet margins in conformity with 100 the margin of the hat brim.

2. A protector for hats constructed of impervious and imperforate material, and shaped to conform with the crown and brim 105 of the hat, and to cover both the exterior and interior of the hat, and an element carried by the protector for designating the material of the hat covered by the protector.

3. A hat protector comprising an element constructed of imperforate material and 110 shaped to conform with the hat crown and brim and arranged to be placed within the

hat crown and underlying the hat brim; a second element constructed of imperforate material shaped to conform with the hat, a portion of which is arranged to cover the outside of the hat crown and overlying the hat brim, and means for uniting the margins of said elements.

In testimony whereof, I have signed my name to this specification, in presence of two subscribing witnesses.

LEON COHEN.
